UNITED STATES PATENT OFFICE

HENRY A. REEDY, OF ST. PAUL, MINNESOTA

PHOTO-PRINTING MACHINE

Application filed June 22, 1929. Serial No. 373,011.

This invention relates to a photo-printing machine adapted to print simultaneously from a glass plate and from a relatively thin film.

As is well known in this art, there is a class of work involving the printing of pictorial illustrations upon cards or the like which also require lettering or reading matter, the pictorial element being transferred to the card from a thin photographic film and the reading matter requiring the use of a glass plate. Holiday greetings and the like constitute a large part of this class of printing. Heretofore it has been common practice to run such work through a printing machine twice, with adjustments for the different requirements of the film and plate between runs. Obviously, such procedure is slow and expensive.

It is my object to eliminate the repeated handling of the stock for the successive printing operations by simultaneously performing the two classes of work. Another object is to provide a photo-printing machine adapted to facilitate making adjustments for commercial printing from films and plates simultaneously. The invention also includes certain other features of construction which will be more fully pointed out in the following specification and claims.

In the drawings which illustrate the best form of my invention at present known to me, Figure 1 is a perspective view of the machine with the operating lever and platen raised; Fig. 2 is a plan view of the device with the cover including the printing surfaces, platen and operating lever removed; Fig. 3 is a typical vertical, transverse section, taken on the line 3-3 of Fig. 4; Fig. 4 is a longitudinal, vertical section taken on the line 4-4 of Fig. 3; Fig. 5 is a fragmentary section taken on the line 5-5 of Fig. 4 and Fig. 6 is a wiring diagram showing the lamp circuits and controls.

The machine has a housing 7 of substantially rectangular shape and a removable top 8 which is normally held in place by suitable hooks 9 at the front and back of the machine. The interior of the housing 7 is divided by a thin, sheet metal partition 10

into light compartments 11 and 12. A second partition 13 separates the compartments 11 and 12 from a space 14 within the front of the housing for a control switch 15. The partition 10 extends vertically from the bottom to the top of the housing and projects at its upper edge between glass plates 16 and 17, the upper surfaces of which constitute the printing surfaces for a photographic plate 18 and a relatively thin photographic film 19 respectively. These printing elements 18 and 19 are suitably supported upon flanges 20 projecting at the edges of an opening 21 in a suitable removable support 22. Parallel guide strips 23 on the top 8 permit lateral sliding movement of the support 22. The glass plate 18 and film 19 are so arranged in the support 22 that said plate projects below the film with its edge arranged to abut against the edge of the partition 10, or adjacent edge of the plate 17. In this manner a positive stop for the edge of the photographic plate 18 is afforded and the proper positioning of the film and plate in registry with the opening in the respective light compartments 11 and 12 is insured.

The opening 21 is formed to retain the sensitized stock to be printed upon in proper registry with the plate 18 and film 19. Removably fitted within the opening 21 is a platen 24 having a padded surface to bear upon the stock. This platen is fixed on a cover 25 which is secured by hinges 26 to the top 8 near its rear edge. Above the cover 25 is mounted an operating lever 27 supplied with a hinge 28 above the hinge 26. A chain 29 connects the lever 27 with the cover 25 to permit limited relative movement, and a coiled spring 30 is arranged to normally raise the lever 27, together with the cover 25 and platen 24, to the positions shown in Fig. 1. The platen 24 is adjustably secured to the cover 25 by bolts 31 which are movable with the platen in slots 32 (Fig. 3) in the cover 25. Thus the platen 24 is movable to conform to the position of the opening 21 in the support 22. A leaf spring 34 fixed on the lever 27 is arranged to distribute the pressure applied by the lever to opposite sides of the cover 100

25 above the platen 24. A rigid stud 35 projects from the lever 27 to engage the movable element of the switch 15. This movable switch element is slideable vertically 5 in the space 14 within the housing and is urged upward by a coiled spring 37 engaging its lower end, a suitable guide socket 38 being provided. As best shown in Figs. 4 and 5, the switch element 15 is formed from 10 insulating material and has an electric conductor 39 extending through it and projecting at opposite sides to simultaneously engage spring contacts 40 when the movable switch element is depressed. The spring contacts 40 constitute terminals of circuit wires 41 and 42.

Within the compartment 12 is a pair of lamps 43 adapted to illuminate the plate 18, and there is also in this compartment a 20 pilot lamp 44 of lesser candle power. The compartment 11 contains a pilot lamp 45 and a relatively powerful lamp 46 for illuminating the film 19. As shown in Fig. 6, the several lamps 43, 44, 45 and 46 are disposed in parallel circuits between the circuit wires 41, 42 and another line wire 47 for supplying electrical power. It will be evident that the lamps 43 and 46, in the arrangement shown, are controllable by the 30 switch 15. A rheostat 48 is placed in series with the lamps 43 to control their illumination, this rheostat, as shown in Figs. 1, 2 and 4, being conveniently mounted upon the back wall of the housing 7.

35 The lamp 46 is preferably made adjustable horizontally and parallel to the partition 10 so as to give the most advantageous distribution of light. To this end, the lamp socket is made slideable in the compartment 40 11 and a rod 49 is secured to the socket and projects through an opening in the housing 7 where it may be manipulated to move the lamp.

In use, the film and plate for commercially printing cards of a particular size are 45 mounted in a suitable support 22 having an opening 21 adapted to receive the sensitized card stock. The plate 18 and film 19 are secured edge to edge, as indicated in Fig. 1, 50 within the opening 21 and are supported upon the flanges 20 in such a manner that the lower surface of the plate 18 is offset downward from the film, as indicated in Fig. 3. The support 22 is now placed between the guide strips 23 and moved laterally to bring the edge of the plate 18 against the upper edge of the partition 10, as shown in Fig. 3. Thus the plate 18 is located in proper relation to the light compartment 12 55 and the film 19 is held in proper position at the opposite side of the partition 10 so as to be illuminated by light from the compartment 11. The position of the platen 24 is now adjusted by means of the bolts 31 to 60 register with the opening 21. With the

70 lamps connected in a suitable electric circuit, as shown, a card or other sensitized sheet may be placed in the opening 21 and the exposure made by merely operating the lever 27 forward and downward until the stud 35 closes the switch 15, the lever being held in depressed position for the period required for the exposure. As will be readily understood, closing the switch 15 closes the circuits for the lamps 43 and 46. The operator merely releases the lever 27 to terminate the exposure. By adjusting the rheostat 48, the intensity of the light from the lamps 43 may be adjusted to meet the requirements of the particular plate 18 employed in the printing. Obviously, when the machine is once adjusted, a large number of cards or sheets of stock may be exposed in rapid succession and the printing 80 from the film and plate is simultaneously 85 accomplished by a single handling of the stock.

90 It will now be understood that the partition 10 extends upward through the printing surface to divide it for the film and plate and that the printing surface for the film is offset upward from that for the plate by my arrangement of the relatively thick glass closure 17 forming the printing surface 95 for the film.

Having described my invention what I claim is new and desire to protect by Letters Patent is:

1. In a photo-printing machine, a pair of 100 light compartments having a common wall between them and each formed with an opening adjacent to said wall, means for mounting a photographic plate and a relatively thin film with their adjoining edges in alignment with said wall, and with their 105 upper surfaces in substantially the same plane in positions for exposure in said openings respectively, means for severally illuminating said compartments and means for retaining sensitized stock in printing relation to said film and plate to secure simultaneous exposures therefrom.

2. In a photo-printing machine, a pair of 110 light compartments having a common wall between them and each formed with an opening adjacent to said wall, relatively elevated and depressed supports for a photographic plate and a relatively thin film in registry with said openings respectively, means for severally illuminating said compartments, means for adjusting the brilliancy of illumination in at least one of said compartments, and means for retaining sensitized stock in printing relation to said film and plate to secure simultaneous exposures from said film and plate.

115 3. A photo-printing machine comprising a housing, a partition dividing said housing into separate light compartments, said compartments each having an opening adjacent 120

to said partition, glass closures for said posures therefrom and an operating member adapted to actuate said switch to light said lamps upon the movement of said cover to operative position.

5 In testimony whereof, I have hereunto signed my name to this specification. 70

HENRY A. REEDY.

6 simultaneously retaining a photographic plate and film upon said surfaces respectively and means for retaining sensitized stock to be exposed in registry with said film and plate to simultaneously print therefrom.

10 4. A photo-printing machine comprising a housing, a partition dividing said housing into separate light compartments said compartments each having an opening adjacent to said partition, glass closures for said

75

15 openings constituting printing surfaces respectively for photographic plates and films, the surface for said film being offset outward from the surface for said plate, means for illuminating said compartments,

80

20 a support for retaining a photographic plate and film upon said surfaces respectively and means for retaining sensitized stock to be exposed in registry with said film and plate.

85

25 5. A photo-printing machine comprising a housing, a partition dividing said housing into separate light compartments, said compartments each having an opening adjacent to said partition, separate glass closures for

90

30 said openings printing surfaces in different planes respectively for photographic plates and films, said closures being separated by said partition, means for illuminating said compartments, means for retaining a photographic film and plate upon said surfaces respectively and means for positioning sensitized stock in registry with said film and plate for simultaneous exposure.

95

35 6. In a photo-printing machine, a pair of light compartments having a common wall between them and each formed with an opening adjacent to said wall, means for mounting a photographic plate and a film

100

40 edge to edge for exposure at said openings respectively, said wall forming an abutment for an edge of said plate adjoining said film, means for severally illuminating said compartments and means for retaining sensitized stock in printing relation to said

105

45 film and plate to secure simultaneous exposures from said film and plate.

110

50 7. In a photo-printing machine, a pair of light compartments having a common wall between them and each formed with an opening adjacent to said wall, means for mounting a photographic plate and a film with their adjoining edges in alignment with said wall, and with the film and plate

115

55 in positions for exposure in said openings respectively, electric lamps for severally illuminating said compartments, a control switch for said lamps, a cover for retaining sensitized stock in printing relation to said

120

60 film and plate to secure simultaneous exposures from said film and plate.
